UNITED STATES PATENT OFFICE.

HECTOR LE DOUX, OF WORCESTER, MASSACHUSETTS, ASSIGNOR TO CROMPTON & KNOWLES LOOM WORKS, A CORPORATION OF MASSACHUSETTS.

WOVEN PILE FABRIC.

1,096,510.

Specification of Letters Patent. Patented May 12, 1914.

Application filed September 24, 1913. Serial No. 791,513.

To all whom it may concern:

Be it known that I, HECTOR LE DOUX, a citizen of the United States, residing at Worcester, in the county of Worcester and 5 State of Massachusetts, have invented certain new and useful Improvements in Woven Pile Fabrics, of which the following is a specification.

My invention relates to woven pile fabrics, 10 and particularly to that class of pile fabrics which is woven double, by carrying the pile warps back and forth between suitably spaced backing webs, and interweaving the pile warps with each of the backing webs, 15 said pile warps being afterward cut midway between the backing webs, so that each will have a cut pile facing or surface thereon.

My invention more particularly relates to woven pile fabric used for cocoa mats, etc., in 20 which the warp, and pile are of heavy and coarse character.

The object of my invention is to improve upon woven pile fabrics of the class referred to, and to provide a woven pile fabric of the 25 class referred to, which can be woven on an automatic loom which is preferably provided with needles for inserting the weft threads.

In my improved woven pile fabric, the two backing webs are preferably of uniform structure, 30 each having weft threads extending in substantially the same horizontal plane, and two sets of binder warps, crossing each other at regular intervals upon the weft threads, to bind and hold said weft threads, and each 35 backing web also having a second set of weft threads, extending upon the outerside of the binder warps, and in the same vertical plane as the first mentioned weft threads, and two sets of pile warps, passing back and forth 40 between the two backing webs, and passing around the weft threads on the outer side of the backing webs, said pile warps crossing each other intermediate the backing webs, prior to being cut to form a cut pile surface, 45 and each set of pile warps forming close loops on the backing webs, to make what is termed a "diamond" back on the woven fabric.

My invention consists in certain novel 50 features of construction of my woven pile fabric as will be hereinafter fully described.

In the drawing is shown a detached section of a woven double pile fabric embodying my improvements; the section is taken

in the direction of the length of the fabric, 55 and at the right the pile warps are shown cut, intermediate the backing webs, to produce a cut pile surface on each fabric.

In the accompanying drawing, 1, and 2 are two sets of binder warps in one backing 60 web, which are crossed at regular intervals, to bind and hold the weft or filling threads 3, which are inserted through the shed, preferably by means of a needle. 4, and 5 are two sets of binder warps in the other backing 65 web, which are crossed at regular intervals, to bind and hold the weft threads 6, which are inserted through the shed, preferably by means of a needle.

7 and 8 are the two sets of pile warps 70 which are carried back and forth between the two sets of binder warps 1 and 2, and 3 and 4, and are crossed, as shown at the left in the drawing, intermediate said two sets of binder warps. With the two sets of binder 75 warp threads 1 and 2 is combined an outer set of weft threads 9, which extend in the same vertical plane as the weft threads 3, and with the other set of binder warp threads 4 and 5, is combined an outer set of 80 weft threads 10, which extend in the same vertical plane as the weft threads 6. The set of pile warps 7 pass around the outer weft thread 9 on the upper backing web, and then around the outer weft thread 10 on the 85 lower backing web, said outer wefts 9 and 10 are not in the same vertical plane, as shown at the left in the drawing. The sets of pile warps 8 pass around the outer weft thread 10 on the lower backing, and then 90 around the outer weft thread 9 on the upper backing, said outer weft threads 10 and 9 are not in the same vertical plane, so that the two sets of pile warps 7 and 8, form two sets of close loops, arranged alternately on 95 the back of the backing webs, and forming what is termed a diamond back. After the fabric is woven, as shown at the left in the drawing, the sets of pile warps 7 and 8 are cut or severed, intermediate the two backing 100 webs in any ordinary way, forming two separate pile fabrics, each having a cut pile facing or surface, as shown at the right in the drawing.

My improved double pile fabric may be 105 woven on any suitable type of automatic loom, and parts of a loom particularly adapted for weaving said fabric, are shown

and described in an application for Letters Patent, Serial No. 790,327, filed September 17, 1913.

Having thus described my invention, what I claim as new and desire to secure by Letters Patent is:—

1. A woven pile fabric having a backing web composed of binder warps crossed at regular intervals, weft threads between said binder warps, weft threads on the outer side of said binder warps, and in substantially the same vertical plane as the inner weft threads, pile warps inclosing said outer weft threads, to form a close loop thereon.
- 15 2. A double woven pile fabric, having suitably spaced backing webs, each composed of binder warps crossed at regular intervals, weft threads between said binder warps, weft threads on the outer side of said binder warps, and in substantially the same vertical plane as the inner weft threads, and two sets of pile warps, crossing each other between the two backing webs before being severed, and passing around the outer weft threads, to form close loops thereon.
- 20 25 3. A double woven pile fabric, having suitably spaced backing webs, each composed of

binder warps crossed at regular intervals, weft threads between said binder warps, weft threads on the outer side of said binder warps, and in substantially the same vertical plane as the inner weft threads, and two sets of pile warps, crossing each other between the two backing webs before being severed, and passing around the outer weft threads to form two sets of close loops thereon, and when severed, intermediate the backing webs, forming a cut pile surface.

4. A woven pile fabric having a backing web, composed of binder warps crossed at regular intervals, weft threads between said binder warps, weft threads on the outer side of said binder warps, and in substantially the same vertical plane as the inner weft threads, pile warps inclosing said outer weft threads to form a close loop thereon, and also inclosing the inner weft threads, lying in substantially the same vertical plane as said outer weft threads.

HECTOR LE DOUX.
